UNITED STATES PATENT OFFICE

LEON BENOIT, OF CHICAGO, ILLINOIS

FILLER FOR EGG CARTONS AND THE LIKE

Application filed April 18, 1930. Serial No. 445,276.

This invention relates to a filler construction such as is suited for the reception of eggs and other like commodities which require separation in individual cells or compartments. The present improvements are directed toward a filler which may be collapsed with a minimum of interference between its intersecting walls, and toward means by which the partitions and/or cross walls forming the filler may be shifted, as required, to accommodate eggs or other articles varying slightly in size.

An exemplification of my invention is set forth in the accompanying drawing where-

15 in—
Figure 1 is a view in perspective of a filler set up ready for the reception of eggs or other desired contents;

20 Fig. 2 is a transverse section through the filler;

Fig. 3 is a fragmentary elevation of one side of the filler;

Fig. 4 is a view in elevation of the filler, as it appears when collapsed; and

25 Fig. 5 is a view in plan of the filler in collapsed condition.

The present filler is built up of a series of longitudinal partitions A in the form of strips in intersection with transverse cross walls B each in the form of a card. The number and arrangement of such partitions and cross walls is determined according to the size and capacity of the filler to be produced thereby. Each of the cross walls may 30 have one or more ventilating windows 6, preferably in its upper region, thereby providing for the circulation of air through all the cells or compartments of the completed structure.

35 40 Each of the cross walls is formed with a series of slots 7 extended inwardly from one edge, the number of such slots corresponding with the longitudinal partitions which are used. As shown, four such slots are provided, each proceeding inwardly from the bottom edge 8 of the cross wall, with a flaring entrance 9 adjacent which is a shoulder 10 on one side and, at a higher point upon the opposite side, an elbow 11. Beyond the elbow the proximate slot side 12

continues slantingly to define in area of maximum width at the inner end of the slot.

Associated with a plurality of cross walls so formed are the partitions having like formations in each instance. As shown, each partition is of a vertical height considerably less than that of the cross walls so that the latter alone extend to the upper plane of the filler. Each partition is provided with opposite pairs of slots 15 and 16 extending inwardly from its upper and lower edges, respectively, the former having flaring entrances 17, as shown. The lower slots are considerably wider than the companion upper slots for a purpose which will presently appear.

55 60 65 In the assembly of the partitions with the cross walls the former are moved past the shoulders 10 and elbows 11 to the position shown in Fig. 2, where the lower edges of the partitions are brought into substantially the same plane as the corresponding edges of the cross walls. In executing these movements the shoulders 10 will be required to 70 75 yield somewhat in order that the partitions and cross walls may arrive at the final positions noted, but thereafter the several intersecting walls of the filler will be retained against disassembly by reason of the lock 80 85 afforded by the shoulders which co-act with the partitions to prevent reverse movement of the latter. In the final position shown in Figs. 2 and 3, the partitions may stand upright against the vertical edges of the slots 7, or slant to one side adjacent the inclined edges 12 of these slots. By providing four such partitions arranged in pairs, as shown, two troughs extending lengthwise of the filler are produced. The cross walls may 90 95 also have capacity for shifting angularly within the partition slots to the extent that it is permitted by the width thereof. Such an adjustment from the normal vertical position is desirable in order to accommodate eggs or articles of varying size.

A filler of the kind described may, on occasion, be collapsed to the positions indicated in Figs. 4 and 5. In executing this movement the cross walls are first straight-

ened up against the vertical edges of the slots 7 following which the components of the filler may be swung relative to each other into a state of collapse so as to occupy a minimum of space. In arriving at this position, the shoulders 10, which are necessarily weak because of their small size and the displacement they are subjected to when assembly of the partitions takes place, will swing around into the space afforded by the widened slots 16. This is of advantage because otherwise the shoulders would be required to bend laterally when striking against the partitions in this collapsed position.

By the construction herein described, I have provided a filler which may be advantageously produced and assembled, and, when placed in use, will have capacity for such adjustments as are required for the accommodation of articles varying in size and contour. In addition, the construction is one which securely holds the components of the filler together prior to its being set up for use, and without damage or injury to the operative parts thereof. Such a filler may be used independently of any surrounding carton, or, if preferred, may be placed within a carton, wrapper, or other container for convenience and further protection in handling and use.

I claim:

1. A filler in which is comprised a series of cross walls in intersection with a series of partitions, the slots of the cross walls having means engaging the partitions for preventing disassembly of the latter, and being shaped to permit of swinging movement of the partitions from an upright to a slanting position, the partitions having slots wherein the cross walls are engaged, such

slots being of uniformly greater width than the thickness of the cross walls to permit of angular movement of the cross walls whereby to accommodate articles of varying size in the cells provided by the intersecting walls and partitions.

2. A filler in which is comprised a plurality of slotted cross walls in intersection with a plurality of slotted partitions, there being locking means extended into the slots of the cross walls and widened spaces adjacent thereto in the slots of the partitions, the slots of the cross walls being further provided with opposite edges one of which is vertical and the other of which is slanting to permit the cross walls engaged therein to assume vertical or slanting positions, as desired, and the widened slots of the partitions being of materially greater width than the thickness of the cross walls to permit angular movement of the cross walls therein, the locking means extending across the slots of the cross walls being brought into engagement with the widened portions of the slots of the partitions when the cross walls are shifted angularly, and such locking means being receivable within such widened portions without interference with the partitions when the cross walls and partitions are swung upon each other into a condition of collapse.

3. A filler comprising two series of walls in intersecting relation, one series of walls having means complementary to and coacting with means in the other series of walls, the means of each series of walls being configured to permit independent swinging movement of the walls of each series through a limited distance into and out of vertical position.
